UNITED STATES PATENT OFFICE.

RICHARD R. KINNEY, OF KALAMAZOO, MICHIGAN, ASSIGNOR OF ONE-HALF
TO WILLIAM L. BARTH, OF COLDWATER, MICHIGAN.

BURIAL APPARATUS.

SPECIFICATION forming part of Letters Patent No. 630,459, dated August 8, 1899.

Application filed March 11, 1897. Serial No. 627,053. (No model.)

To all whom it may concern:

Be it known that I, RICHARD R. KINNEY, a citizen of the United States, residing at the city of Kalamazoo, in the county of Kalamazoo and State of Michigan, have invented certain new and useful Improvements in Burial Apparatus, of which the following is a specification.

My invention relates to improvements in burial apparatus, and particularly to an improved mechanism for lowering coffins or caskets into the grave. Several different styles of apparatus have been produced for this purpose. In all prior devices either the control of the lowering device is not positive or else some mechanical motor has been employed which operated very slowly, requiring the expenditure of considerable labor at the time.

The objects of my invention are to provide an improved apparatus for lowering coffins into the grave that is positive in its operation and yet under complete control, so that the coffin or casket can be properly and evenly lowered to the bottom of the grave; second, to provide a new and improved controlling means for such purposes; third, to provide a compact and efficient device for the purpose; fourth, to provide an improved means of automatically releasing the lowering-cords in such a device, and, fifth, to provide a mechanism for the purpose that is safe as well as efficient.

Further objects will appear definitely in the detailed description to follow.

I accomplish these objects of my invention by the devices, mechanism, and means described in the following specification, pointed out in the claims, and illustrated in the accompanying drawings, in which—

Figure 1 is a top plan view of the same, with portions of casing broken away to show details of construction and the parts near the guiding-sheaves shown in section to show the relation of parts. Fig. 2 is an enlarged detail plan view of the winding-drum and actuating or controlling mechanism at one end thereof, showing adjacent parts. Fig. 3 is an enlarged detail plan view of a portion of the pump and the controlling-cylinder connecting-pipes and valves. Fig. 4 is an enlarged

detail sectional elevation, taken on line 4 4 of Fig. 2, showing the lever or handle for the pump. Fig. 5 is an enlarged transverse detail sectional elevation taken on line 5 5 of Fig. 3. Fig. 6 is an enlarged detail sectional longitudinal elevation taken on line 6 6 of Fig. 5, showing a portion of the pump, controlling-cylinder, valves, and connections. Fig. 7 is an enlarged detail sectional elevation taken on line 7 7 of Fig. 2, showing the safety-dog and ratchet for the controlling-shaft. Fig. 8 is an enlarged detail elevation of the corner of the case shown in Fig. 2, showing the head of shaft C and lever for controlling the same. Fig. 9 is a detail plan view of one of the adjustable hangers for the guiding-sheaves, showing the sheave and the guiding-arms N for the automatic detaching device. Fig. 10 is a detail sectional elevation on line 10 10 of Fig. 9. Fig. 11 is an enlarged detail view of one of the guiding-arms N, showing a stop and eye T for cord e'. Fig. 12 is an enlarged detail sectional view on line 12 12 of Fig. 11. Fig. 13 is an enlarged detail longitudinal sectional view of one of the automatic detaching devices, taken on line 13 13 of Fig. 1. Fig. 14 is an enlarged detail view showing the method of hinging the parts of the frame or casing together.

In the drawings similar letters of reference refer to similar parts throughout the several views, and all of the sectional views are taken looking in the direction of the little arrows at the ends of the section-lines.

Referring to the lettered parts of the drawings, A represents a frame made of a rectangular casing corresponding in size to the top of a grave. The ends of the casing are divided and hinged together on the under side by the hinge f, so that one side can be folded upon the other during transportation. In one end B of the casing is supported on suitable bearings a shaft C, which is divided at its center and joined together by sleeve-union U to permit the shaft to separate when the frame is folded for transportation and permit the parts of the shaft to join when the case is opened out for use. On each end of this shaft is a winding-drum C', and from each drum extends a pair of cords or ropes e' e'. These cords are guided by suitable

guiding sheaves or pulleys *e*, which are supported on suitable brackets inside the casing. The cords extend from these sheaves inwardly toward the center of the frame over 5 the guiding-sheaves *c*. The sheaves *c* are supported on adjustable brackets *S*. To each bracket *S* is pivoted an adjustable guiding-arm *N*, the use of which will hereinafter be explained. Each arm *N* is provided with an 10 adjustable stop *N'* to indicate the correct position of the coffin or casket to be placed thereon when they receive the load to be lowered. The ends of the cords *e'* are provided with elongated links *e''*. These cords are the 15 means by which the casket or coffin is lowered into the grave, the work being accomplished by a proper controlling of the windlass or drum *C' C'*, which will be definitely described later. The cords *e'*, extending from 20 opposite each other, are drawn together and project into the automatic detaching block or casting *M* provided for each pair. The ends of each block contain suitable openings, in which are inserted suitable pins *M'*, having 25 double points *r' r'*. One of the points of the pins *r'* is longer than the point *r*. These are rested against suitable shoulders in the device, and pin *r'* projects beyond the bottom of the block *M*. The shorter pin *r* is slightly 30 hooked and engages the link *e''* on the end of its corresponding cord. The sides of the block *M* are made flat, and the guiding-arms *N* rest against the same to hold them in position till the load is adjusted. The cords *e'* 35 extend through eyes *T*, secured to the sides of the arms *N*, and, when the cords are lowered under the load, carry down the arms out of the way as the coffin descends. From this description it is clear that when the cords and 40 device are in position to receive a load the detaching device *M* is held in position by the guiding-arms *N*. When the load is lowered, the cords, acting on the arms *N* through the eyes *T*, carry them down out of the way. 45 When the coffin reaches the bottom of the grave, the elongated ends *r'* of pins *M'* strike the bottom first and are pressed up, carrying the short ends *r* out of the links *e''*, releasing the cords, which can then be removed. 50 On the shaft *C* is situated a ratchet-wheel *D*, with a dog *D'* on its under side. The teeth of the ratchet-wheel are of such form that they retain the dog until the ratchet is moved back to release the same, which is done by the bar *R*. This device relieves all strain on the controlling mechanism till it is released 55 when the time comes for lowering.

On the shaft *C*, preferably at one end, is a reel or drum *C''*, to which is attached the controlling tape or belt *E''*. This is secured to the end of a piston-rod *E'*, which extends from a cylinder *E*, where the same is controlled by a piston under fluid-pressure. The fluid preferred by me consists of a mixture of alcohol and water which will not freeze. Water may be used when the temperature permits. 60 I provide a pump *F*, having a piston *F'*

and pump-rod *F''*, operated by lever *L* and handle *L'*, as clearly appears, for pumping the fluid through the pipe *G* from the bottom of the cylinder *E*, around through pipe *P*, and past the check-valve *P'* into the top of the said cylinder *E*. This forces the piston toward the bottom, which through its connection with the belt *E''* to reel or drum *C''* actuates the 70 shaft *C*, causing the windlass *C'* to wind up the cords *e'* into position for operation. When the same has been pumped up until the cords *e'* are at the top and the blocks are held in 75 position to receive the load.

An exhaust-pipe *H*, with valve *H'*, connecting the top of the cylinder *E* with pipe *G* to permit the escape of fluid from cylinder *E*. The valve *H'* is controlled by lever *K''*, which operates the same through any suitable connections. The connection shown consists of chain *K* over sheave *K'*, rod *J'*, connected to said chain and drawn back by spring *K''*, intermediate lever *J*, with stop *i*, and link *I'*, connected to handle *I* of the valve. Pressure 90 on lever *K''* opens the valve *H'* and permits the fluid to escape to the top of the cylinder *E* and allows the reel or drum *C''* to revolve, which unwinds the cords *e'* and allows the coffin or load to descend. 95

When my improved burial mechanism is in place, the coffin or casket is placed on the central supports in the position indicated by the guides *N'*. When all is ready, the operator inserts his lever *R* in the head on the end of shaft *C* and moves the same till he releases the dog *D'*, which drops out of the engagement. The lever *R* is then removed. The lever *K''* is then depressed and through its connections opens the valve *H'* the amount 100 required to lower the coffin at the required speed. After the coffin is lowered the cords can be partially raised out of the way by rotating the shaft backward by the lever *R*. 105

Having thus described my improved burial apparatus, I desire to state that it can be considerably varied in its details without departing from my invention. In connection with the remaining apparatus other automatic releasing devices might be employed than those 110 I have shown, and the releasing device is capable of use elsewhere. The exact position of the controlling-cylinder *E* is not material. It might be located in some other place in an independent casing from the remainder of 115 the device, though the position in which I have shown it is preferred by me. I also desire to state that it may be possible to dispense with the guiding-arm *N* for retaining the detaching device *M* in position, though 120 the same as used by me retains all the parts nicely in position and is easily controlled and is out of the way when not in use. As I have intimated before, other connections might be provided for the pump than those I have 125 shown.

I desire to state that other coupling devices than the sleeve *U* might be employed for the shaft *C*, and for that matter the entire frame

might be made non-folding, though that would not be convenient for transportation. The casing B' over the end B is made hinged, so that it can be opened for the inspection of the 5 parts. The lever L is made removable, so that all can be easily incased.

Having thus described my invention, what I claim as new, and desire to secure by Letters Patent, is—

- 10 1. In a burial apparatus the combination of a suitable frame corresponding in dimensions to the top of a grave, the ends of which frame are divided; a suitable hinge between the parts of the frame; a controlling-shaft on one 15 end of the frame divided into two parts detachably joined together; winding-drums on said shaft; means of controlling the same; and cords or belts extending therefrom through suitable guides to the middle of the frame for 20 the purpose specified.
- 2. In a burial apparatus the combination of suitable lowering cords or belts; a block M, between opposite cords; pins M', with double points r, r', in the ends of said block M, the 25 point r', of which is longest and projects below the bottom of the block; and link e'', on the cords to engage the shorter part r; so that when lowered to the bottom the pin will be 30 pressed up by the longer part r', striking the bottom so automatically releasing the cords or belts as specified.
- 3. In a burial apparatus the combination of a suitable frame corresponding in dimensions to the top of a grave; lowering cords or belts 35 projecting oversuitable guides from the sides to the space at the center of the frame; an automatic detachable connection at the center between the cords or belts consisting of a block and downwardly-projecting connect- 40 ing-pins at each end; and pivoted arms N, on each side of the frame projecting toward the center to retain the connection in position at that point for the purpose specified.
- 4. In a burial apparatus the combination of 45 a suitable frame corresponding in dimensions

to the top of a grave; lowering cords or belts projecting over suitable guides from the sides to the space at the center of the frame; an automatic detachable connection at the center between the cords or belts consisting of 50 a block and downwardly-projecting connecting-pins at each; pivoted arms N, on each side of the frame projecting toward the center to retain the connections in position; and stops N', on the arms N, to indicate the correct position of the load for the purpose specified. 55

5. In a burial apparatus the combination of a suitable frame corresponding in dimensions to the top of a grave; lowering cords or belts suitably guided thereon; mechanism for controlling said cords; a hydraulic cylinder with its piston connected thereto by a suitable belt; a force-pump with pipes connecting the top and bottom of said cylinder; and a pipe with a stop-cock valve therein connecting the 60 top and bottom of the cylinder for the purpose specified. 65

6. In a burial apparatus, the combination with oppositely-lowering cords or belts bearing-links at their lower ends, and a detachable 70 block at the center having pins toward each end thereof which are double-pointed, one of which points projects below the under side of the detachable block and the other of which is considerably shorter in length, the said pins 75 being considerably guided within the block and the shorter limb of which is detached to engage the links of the lowering cords or belts, so that when a load is on the central block and it is lowered to the bottom the longer portion of the pin strikes the bottom and forces the shorter portion to disengage the link and release the belt, substantially as described. 80

In witness whereof I have hereunto set my hand and seal in the presence of two witnesses. 85
